FOREIGN PATENT DOCUMENTS

DE 10 2008 002 727 12/2009

Primary Examiner — Robin V Webster(74) *Attorney, Agent, or Firm* — Robert Curcio; DeLio, Peterson & Curcio, LLC(57) **CLAIM**

We claim the ornamental design for a “filtration system,” as shown and described.

DESCRIPTION

FIG. 1 is the front view of the filtration system according to the present invention;

FIG. 2 is back view of the filtration system according to the present invention;

FIG. 3 is left-side view of the filtration system according to the present invention;

FIG. 4 is a right-side view of the filtration system according to the present invention;

FIG. 5 is a top view of the filtration system according to the present invention;

FIG. 6 is a bottom view of the filtration system according to the present invention;

FIG. 7 is a top perspective view of the filtration system according to the present invention; and,

FIG. 8 is a bottom perspective view of the filtration system according to the present invention.
